UNITED STATES PATENT OFFICE.

WILLIE EASON WILLIAMS, OF BALTIMORE, MARYLAND.

STRUCTURE OF STRENGTHENED CONCRETE.

SPECIFICATION forming part of Letters Patent No. 738,268, dated September 8, 1908.

Application filed March 21, 1903. Serial No. 148,918. (No model.)

To all whom it may concern:

Be it known that I, WILLIE EASON WILLIAMS, a citizen of the United States, residing at Baltimore, in the State of Maryland, have invented certain new and useful Improvements in Structures of Strengthened Concrete, of which the following is a specification.

This invention relates to structures of concrete strengthened with iron, and more especially to beams or girders of concrete fixed at both ends and strengthened by the peculiar arrangement of certain steel bars and binding devices which are embedded within the concrete and so disposed as to effectively resist all the strains to which the structure is subjected, as will hereinafter fully appear.

The object of the invention is to provide in concrete beams a strengthening structure of steel in which the elements employed are of such form and are so disposed in the concrete that without increasing the quantity of strengthening material usually employed in such structures more effective resistance is obtained to the strains to which the beams are subjected than in beams as hitherto constructed.

A special object of the invention is to provide an anchorage by means of which the end of a beam embedded in the side wall of a building may be so securely associated therewith that no separation of the beam and the wall is possible.

A further object of the invention is to provide an improved form of binding device for securing steel rods in position in concrete beams and the like by means of which the strains upon the steel rods will be distributed through the concrete.

Another object of the invention is to connect the parts of the strengthening structure without riveting or the assistance of bolts, so that the various elements of the structure will have unitary action in resisting strains of tension, compression, and flexion.

In the description of the invention reference is had to the accompanying drawings, forming a part of this specification, in which corresponding parts are designated by the same characters of reference throughout the various views, and in which—

Figure 1 is a diagrammatic view showing the arrangement of the steel strengthening

structure in a beam having one end embedded in a vertical wall and extending over a supporting-column. Fig. 2 is a plan view of the strengthening structure used in the embedded end of the beam shown in Fig. 1. Fig. 3 is a plan view of the strengthening structure of a beam over a supporting-column between the ends of the beam, which are embedded in the walls of a building. Fig. 4 is a vertical transverse section through the center of a beam constructed as indicated in Fig. 1. Fig. 5 is a vertical transverse section of a beam on the line 5-5 of Fig. 1. Fig. 6 is a view of one of the double-looped binding devices in position near one end of a beam.

Referring to the drawings by reference characters, A designates a vertical wall having one end of a beam embedded therein, and B represents a column supporting the beam between adjacent bays.

In the following description the beam will be regarded as extending from the wall A to a similar wall, which is not shown, and as much of the beam as lies between A and B will be called a "section."

In all beams constructed according to this invention straight horizontal bars or rods 11 are placed within each beam, near the bottom thereof, and extend through one section from the support at one end to that at the other, but do not cross over into the next section. The rods 11 are parallel, as shown, and at each point of support intermediate the walls of the building the rods in the sections of the beam lying in adjacent bays are lapped over the supporting-columns, as shown in Fig. 1. In each section of a beam a symmetrically-bent rod 2, having a central horizontal portion, is placed in position with the central horizontal portion between the rods 11 and in the same plane therewith. From either end of the horizontal portion of the bar 2 there extends upward toward the top of the beam an inclined portion 2^a, which terminates at the end of the beam-section in a horizontal portion 2^b, which extends over the support for the end of the section, and in case the support is of the form shown at B the end of the curved portion extends over said support to the farther side thereof. The horizontal rods 11 and the symmetrically-bent rod 2 in each section are so disposed in order to effectively

resist the strains of tension in the middle of each section and the strains of flexion near the ends of the section, and rods of the form shown have long been well known in the art.

5 I do not desire to claim them as my invention; but the use of a single bent-rod between a pair of straight rods, together with the binding devices presently to be described, is, so far as I am aware, a novelty in beams of strength-
10 ened concrete.

In order to give additional resistance to the strains of flexion in the ends of the beams, I provide the bars 3, bent into loops, as shown, or the straight bars 4. The loops 3 are used
15 only at the embedded ends of the beams, and the loops encircle vertical anchorage-rods 5, whose ends project above and below the beam and are embedded in the material of which the wall is composed. The rods 4 are used
20 over the supports of the beam intermediate of its ends to connect the sections of the beam in adjacent bays.

In order to effectively hold the rods 3 and 4 in position in the beams, I use the double
25 binding-loops 7, disposed at right angles to the rods 3 and 4 and having the ends and central inclined portions extending downward into the body of the beam, as shown. At the embedded ends of the beam the vertical anchorage-rods hold the looped rods 3 firmly in position
30 over the support for the beam and over the intermediate supports, as B. Where such a construction is impracticable, the prolongation of the rods 4 into adjacent sections of the
35 beam and the use in each section of binding devices 7 serve the same purpose.

In order to hold the rods 1 1 firmly in position in the beam and to connect the terminal portions of the bent rods 2 therewith, I provide the double-looped binding devices 6,
40 which are placed in the beam in the position indicated in the drawings, the terminals and central inclined portions being directed upward. These binding devices on either side
45 of the middle of the beam have the upper portions thereof inclined away from the middle point of the beam, as shown, in order to resist most effectively the bending strain upon the beam near its ends.

50 In order to distribute the strain on the rods 1 1 and the central horizontal portion of bent rods 2 through the concrete and to cause such rods to act as a unit in resisting tensional strains on the beam, I provide transverse rods 8, which rest upon the upper surface of rods 1 1 and the horizontal portions of bent rods 2, as shown. By means of the rods 8, which rest upon the upper surfaces of rods 1 1 and 2, the upward reaction of rods 1 1 and 2 to all downward pressure upon the central part
55 of each section of the beam is distributed through the concrete of the beam more uniformly than when no transverse connections are used, for, as will be readily seen, without the rods 8 the upward reaction of each of the longitudinal rods will be exerted only upon the concrete directly above it. By plac-

ing the bent rod 2 between straight rods 1 1 as effective resistance to downward pressure on the beam is obtained as when a rod 2 is placed over each of rods 1 1 and a saving in strengthening material is effected. The double-looped binding devices 6 and 7 are made of round rods of considerable rigidity, and owing to the rigidity of the material and peculiar form of the devices they obtain a very strong hold on the concrete and an enormous strain is necessary to dislodge them. They therefore are much more effective in holding rods 1, 2, 3, and 4 in position than the ordinary single stirrups of strap-iron.

It will be observed that while no bolts or rivets are used to connect the elements of the strengthening structure in beams of concrete and iron constructed in the manner above described they are so disposed in the beam that they act as a unit in resisting the various strains to which such beams are subjected and distribute the strains uniformly through the concrete.

Having thus described my invention, what I claim as new, and desire to secure by Letters Patent, is—

1. In a beam of strengthened concrete comprising a plurality of sections each of which has both ends resting upon suitable supports, the combination of straight suspension-rods in the lower part of each section, said rods terminating over supports at the ends of the sections, bent rods placed one in each section and each having a central horizontal portion disposed in the horizontal plane of said straight rods, and upwardly-inclined portions at either end of said central portion, said upwardly-inclined portions merging into horizontal portions extending over and terminating above the supports of said sections, and short stiffener-rods placed in the upper part of said beam over each intermediate support and extending into the beam-sections on either side of said supports, substantially as described.

2. In a beam of strengthened concrete having the ends thereof embedded in suitable supports, a pair of vertical anchorage-rods extending above and below the beam, and a U-shaped reinforcing-rod encircling each pair of anchorage-rods and having the ends thereof extending into the beam toward the middle thereof, substantially as described.

3. In a beam of strengthened concrete having the ends thereof embedded in suitable supports, a pair of vertical anchorage-rods at each end of the beam extending above and below the beam, and a U-shaped reinforcing-rod encircling each pair of anchorage-rods and having the ends thereof extended into the beam and terminating in downwardly-disposed projections, substantially as described.

4. The combination in a beam of strengthened concrete having the ends thereof embedded in suitable supports, of a pair of vertical anchorage-rods at each end of the beam extending above and below the beam, a U-

shaped reinforcing-rod encircling each pair of anchorage-rods and having the ends thereof extended into the beam, and double-looped binding devices associated with said reinforcing-rods and embedded in the substance of the beam.

5. The combination in a beam of strengthened concrete, of horizontally-disposed rods extending through the beam between adjacent supports, and double-looped binding devices arranged in the substance of said beam and having the upper portions thereof inclined away from the middle point of the beam, substantially as described.

6. The combination in a beam of strengthened concrete, of horizontally-disposed rods extending through said beam between adjacent supports, and transverse, horizontal rods laid loose upon the upper surface of said longitudinal rods and embedded in the substance of the beam, substantially as described. 15
